APPARATUS FOR CONTROLLING
CHEMICAL REACTIONS

Eugene J. Houdry, Ardmore, Pa., assignor to
Houdry Process Corporation, Wilmington, Del.,
a corporation of Delaware

Original application May 8, 1936, Serial No. 78,542.
Divided and this application February 9, 1939,
Serial No. 255,459

2 Claims. (Cl. 23—288)

This invention relates to apparatus for controlling chemical reactions and is a division of the invention set forth in my copending application Serial No. 78,542, filed May 8, 1936, for which a substitute and continuation-in-part application Serial No. 266,010 relating to the process aspects of the invention was filed on April 4, 1939. More particularly, it concerns temperature control of exothermic or endothermic reactions effected in the presence or with the aid of contact masses.

One object of the invention is to adjust the temperature of a gaseous stream by its passage in heat exchange relation with the reaction zone before being admitted to the contact mass. Another object is to effect heat exchange chiefly by radiation to or from the exterior of the reaction zone. Still another object is to maintain substantially constant temperature throughout the reaction zone. Still other objects will be apparent from the detailed description which follows.

While the invention is capable of rather general application, it is of particular value in controlling exothermic reactions, as for example, combustion reactions resulting from treatment of regeneration fumes from catalytic converters after the manner set forth in my aforesaid copending and parent application to prepare the fumes for industrial use, as indicated, for example, in the copending application of myself and R. S. Vose, Serial No. 58,858, filed January 13, 1936 (Patent No. 2,167,655 issued August 1, 1939).

Concrete embodiments of the invention are disclosed in the accompanying drawing, in which:

Fig. 1 is a vertical sectional view through a converting unit, the section being made substantially on the line 1—1 of Fig. 2;

Fig. 2 is a transverse sectional view substantially on the line 2—2 of Fig. 1; and

Fig. 3 is a fragmentary or left half section of Fig. 1, showing a modification.

The apparatus provides a reaction zone for the desired contact or catalytic mass M, defined by a tubular member or casing 5 having screw-threaded connection with a lower header 6 and welded to an upper header member 7. An outlet pipe 8 leads from the upper end of the reaction chamber for the discharge of reaction products, for example, neutral heated regeneration fumes which may be conducted away to suitable apparatus (not shown) for further treatment of any known or desired type. When the fluid issuing from line 8 is inert burned combus-

tion fumes, the treatment may be utilization of kinetic or heat energy in those fumes.

The gaseous material to be treated may enter the lower end of the reaction zone by an inlet pipe 10 extending through header 6. To insure the stream entering the zone at the proper temperature and also to give a measure of control of the reaction, the stream, prior to its admission to pipe 10, may be brought into extended heat exchange with the exterior of the reaction zone, but such heat exchange is confined, primarily to radiation. By preference, the gaseous stream picks up heat progressively as it is caused to traverse the length or depth of the elongate reaction zone. As indicated, feed conduit 11 may be formed in a coil 11a which encircles the reaction zone throughout its length from outlet end 8 to inlet end 10. The turns of coil 11a may be maintained in definite spacial relation to tubular wall 5 of the reaction zone by suitable members such as rods or posts 12 (Figs. 1 and 2) which may be inserted through holes or bores 12a in upper header 7, while the opposite ends are received in sockets 12b in lower header 6. A wire, cotter pin, or other member is inserted through the rods as at 12c to retain them in place. To control the quantity of heat absorbed or radiated by coil 11a per unit of length of the reaction chamber, and to provide for expansion of the stream, coils 11a may be changed in shape or increased in size as they approach inlet 10, this change or increase being effected in stages by the use of sections of pipe of increased diameter or increased surface presented to casing 5, or gradually and progressively as indicated in Fig. 1. The lower end of coil 11a may be joined to inlet conduit 10 by a suitable connection 13. To prevent loss of heat from the unit, an outer casing 14, which is preferably in sections 40 to allow for the pipe connections 11 and 13, is secured to upper and lower headers 7 and 6 in any suitable manner, as by seating the lower end in an annular recess 6a in lower header 6, while the upper end is attached or clamped to header 7 as by a split ring 15. A layer of heat insulating material 16 may be applied to the entire exterior of the unit.

Progressive exchange of heat by radiation may be effected between the feed and the reaction zone in other ways. If it is not desired to change the size or shape of the conduit making up coil 11a, a conduit of uniform size and shape may be utilized, but the pitch of the coil may be increased as lower header 6 is approached by making the coils closer together, thereby increasing the ra-

diating surface. If uneven spacing of the coils is objectionable, the same effect of progressive heat exchange may be secured by providing additional extended surfaces as by attaching plates of different sizes indicated at 11 (Fig. 3) to the conduit coils 11b, as by welding.

In the apparatus units illustrated in the drawing, it is apparent that the gases to be treated are passed through the conduits in radiant heat exchange with the walls which define the reaction chamber and which enclose the catalytic or other contact mass, the rate of heat exchange being controlled to provide accurate temperature regulation of localized portions of the reaction zone to offset tendencies of the latter to absorb or radiate smaller quantities of heat as the temperature of the fluid traversing the coils approaches the temperature of the reaction zone and its contents. Thus, provision is made for controlling increase of the temperature of the reactants at regulated rate by increased surface areas, by baffles, or by other means so as to remove or supply substantially equal amounts of heat from or to all parts of the reaction zone.

One exothermic reaction to which the apparatus is well adapted is in the combustion of carbon monoxide and/or oil vapors which may be present in regeneration fumes issuing from a catalytic converter for the purpose of increasing the energy content of the fumes, which may be thereafter recovered either as kinetic energy or as heat energy or both, as indicated, for example, in the aforesaid copending application of myself and R. S. Vose. The combustion is best effected when a contact mass is employed, which may vary in character, depending upon the temperature at which the gaseous stream enters the combustion chamber. When it enters at high temperatures, as of the order of 1000° F. or more, and contains sufficient oxygen, the contact mass may be mere inert spreading material, but preferably of a highly porous nature, so as to retain oil vapors and the like until combustion is effected, such as pumice, kaolin, firebrick, and other blends of silica and alumina. This material is preferably in the form of lumps, fragments, or molded pieces. When the gaseous stream enters the combustion zone at a temperature below 1000° F., as of the order of 900° F., the contact mass may comprise or contain suitable catalytic material, such, for example, as metallic oxides and compounds, including those of copper, iron, cobalt, nickel and lead. The metals may be utilized directly, as in the form of shavings or turnings, or the metal or metallic compound may be in finely divided form or incorporated in suitable supports such as inert or active blends of silica and alumina of natural or artificial origin, preferably in the form of lumps, fragments or molded pieces.

Other exothermic reactions which may be conducted within casing 5 with the aid of suitable contact mass of known or desired type include synthesis of ammonia from nitrogen and hydrogen, hydrogenation of hydrocarbons and their derivatives, polymerization of hydrocarbons, and regeneration by burning of contact masses which have been contaminated with carbonaceous, sulphur bearing or other combustible deposits as the result of an endothermic or exothermic on-stream reaction.

When the apparatus of this invention is used for controlling temperature of an endothermic reaction zone suitable fluid is admitted to the heat exchange coil at somewhat higher temperature than desired in the reaction zone. Then

the rates at which heat of reaction is supplied to localized portions of the zone are regulated by the increased radiating surfaces of the coil. A few typical endothermic reactions for which this operation is used are the transformation of higher boiling hydrocarbons into lower boiling products, the dehydrogenation of ordinarily gaseous hydrocarbons, and transformation of low anti-knock naphthas and the like into high anti-knock motor fuels.

Suitable or desired cooling or heating medium may be added to the reactants before and/or after they traverse the radiant heat exchange coil or the like to assist in control of the radiant heat exchange between the coil and the reaction vessel and in regulation of the temperature of a reactant fluid as it enters the reaction zone. Such addition to reactants entering the heat exchange and converting unit may be made by valved line 30. When the reaction conducted in casing 5 is strongly exothermic, as for example, in the catalytic combustion of a stream of gases containing burnable components such as carbon monoxide and hydrocarbons, a cooling or heat absorbing medium such as air, or an extraneous fluid such as inert gases, atomized water or steam may be added by line 30 to increase the heat absorbing capacity of the heat exchange coils through decrease of the temperature and/or increase of the bulk of material entering and traversing the same. Further adjustment of the temperature and/or composition of the reactants entering casing 5 may be effected by admitting a portion of the reactants at controlled temperature or a suitable diluent fluid to the stream flowing through line 10, as by valved conduit 31. When it is desired to reduce heat radiation from casing 5 or to increase the rate of absorption of endothermic reaction heat therein in a stream of reactants or other fluid heated to the desired temperature may be added by valved line 30. With certain reactions, as for example, when oxidizing a stream of gases containing burnable components and oxygen or when treating a stream of hydrocarbon starting material elevated temperatures may be obtained in line 11 by effecting controlled combustion therein, as by adding a suitable fuel or a controlled amount of air to the combustion gases or hydrocarbons as the case may be.

The apparatus of this invention provides, among other important advantages, a reaction vessel in which all portions of the desired catalytic or other contact mass are disposed at small and even minimum distance from a heating or cooling surface maintained at predetermined and closely regulated temperature. Thus, each portion of the mass has the quantum of reaction heat produced or absorbed by the reaction effected therein removed from or supplied to an adjacent heat exchange surface with the result that substantially constant and predetermined temperature may be maintained in all portions of the reaction zone.

When it is desirable to utilize a reaction zone having substantial width as compared to its length, the heat removal from or absorption by the outer wall of the reaction chamber may be supplemented by one or more heat exchange conduits of suitable type embedded in the contact mass. Such conduits may be capable of introducing reactants into the mass in addition to controlling temperature of localized portions of the same. Advantageous types of conduits for controlling the temperature of interior por-

tions of the mass by means of reactants or other heat exchange fluid are disclosed in U. S. Patent 1,987,933, issued January 15, 1935 to J. W. Harrison, in U. S. Patent 1,987,636, issued January 15, 1935, to T. B. Prickett and myself; and in U. S. Patent 2,042,469, issued June 2, 1936 to A. Joseph.

Although this invention has been described in connection with regulating the temperature of reactants for the desired endothermic or exothermic reaction, it is to be understood that it is by no means limited to this preferred use. Suitable extraneous heat exchange fluid, for example, mercury, inert gases, fused salts and the like may be passed through the radiant heat exchange conduit or conduits. In such instances, connection 13 between the heat exchange unit and the reaction chamber will be omitted and conduits 11 and 10 will be connected to suitable sources for supplying heat exchange fluid and reactants, respectively, while the heat exchange fluid may discharge from the radiant heat exchange unit to known or desirable means for adjusting the temperature or otherwise treating the same.

I claim as my invention:

1. Apparatus for effecting chemical reactions comprising a catalytic reaction chamber having

5 side and end walls, a conduit spaced from and outside of the side walls and extending lengthwise of the reaction chamber, means for supplying heat exchange fluid for passage through said conduit, said conduit being so constructed and arranged as to provide progressively increasing heat exchange surfaces per unit of conduit length and per unit of reaction chamber length, said heat exchange surfaces facing said side wall to transfer heat by free radiation between said side wall and said conduit in order to regulate the temperature of contact material in said reaction chamber.

10 2. Apparatus for effecting chemical reactions comprising a catalytic reaction chamber having side and end walls, a coil outside said reaction chamber, means for supplying heat exchange fluid for passage through said coil, said coil being so constructed and arranged as to provide progressively increasing heat exchange surfaces per unit of conduit length and per unit of reaction chamber length, said heat exchange surfaces facing said reaction chamber side wall to transfer heat by free radiation between said side wall and said coil in order to regulate the temperature of contact material in said reaction chamber.

EUGENE J. HOUDRY.
